UNITED STATES PATENT OFFICE.

HOBART M. MERIDA, OF SPICELAND, INDIANA.

MAIL-BAG CATCHER AND DELIVERER.

1,292,502.

Specification of Letters Patent.

Patented Jan. 28, 1919.

Application filed March 10, 1917. Serial No. 153,969.

To all whom it may concern:

Be it known that I, HOBART M. MERIDA, a citizen of the United States, residing at Spiceland, in the county of Henry and State 5 of Indiana, have invented certain new and useful Improvements in Mail-Bag Catchers and Deliverers, of which the following is a specification.

This invention relates to improvements in 10 mail bag catchers and deliverers for use in connection with moving trains.

The main object of the invention is to provide a simply constructed and efficient apparatus of this character carried by a 15 train which will automatically receive and deliver mail bags while the train is moving.

Another object is to provide a substitute holder for the mail bags at the station to take the place of the usual crane.

20 With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

30 In the accompanying drawings:

Figure 1 represents a side elevation of a mail bag catcher and deliverer constructed in accordance with this invention and shown applied, and in the act of receiving and delivering mail at a station, one side wall of 35 the receiving box being omitted to disclose the interior thereof, parts being broken away and in section, and

Fig. 2 is a horizontal section taken on the 40 line 2-2 of Fig. 1.

Figs. 3 and 4 are detail sectional views.

In the embodiment illustrated, a portion 45 of a mail car C is shown having the usual door opening D, at one side of which is secured a laterally projecting arm 1 on which this improved train carried apparatus is designed to be mounted. This arm may be made foldable or not as desired.

The improved catcher and deliverer constituting this invention comprises a supporting frame 2 composed preferably of metal arms in the form of bars 3 and 4 connected at their inner ends as shown at 5, said bars inclining downwardly and outwardly from 55 said point of connection. An upstanding supporting rod 6 is here shown bolted be-

tween the meeting ends of the bars 3 and 4 and has a hook 7 at its upper end for detachable engagement with the arm 1 carried by the side of the car. This rod 6 is designed to detachably support the frame 2 at the side of the car and may be placed in position when the train is approaching a station at which it is desired to deliver and collect mail, or it may remain in this position at all times.

The bar 3 which constitutes the front member of frame 2 is preferably folded upon itself midway its ends and the folded portion thereof bolted together throughout the 70 greater portion of its length, the said members of said folded bar being spaced apart at their outer or folded ends to receive between them a depending pivotally mounted arm 8, the function of which will be here- 75 inafter described.

The bar 4 is also folded midway its length and the side members 4' and 4'' thereof are spaced apart throughout the greater portion of the length of said bar to form a loop 80 and are provided with oppositely disposed bearings in which is mounted a shaft 9. Fixed to this shaft 9 is a ratchet wheel 10 with which is designed to coöperate a dog 11 carried by a disk 12 loosely mounted on said 85 shaft. Coiled springs 13 and 14 are wound on said shaft on opposite sides of the ratchet 10 and disk 12, the spring 13 having one end engaged with the side member 4' of the folded bar 4, and its other end engaged with a 90 mail bag delivery hook 15, one end of which is fixed to shaft 9, said spring operating to turn said shaft and normally release the hook or throw it into open position, it being locked against this movement by the en- 95 gagement of the dog 11 with the ratchet 10 and when said dog is released this hook will under the tension of spring 13, fly back automatically into open released position and thereby deliver the mail bags which are carried thereon at the place of deposit desired as will be hereinafter more fully described.

The coiled spring 14 has one end engaged with the side bar 4'' and its other end engaged with the disk 12 and exerts its tension 105 to normally turn said disk in a direction opposite to the turning direction of the ratchet wheel 10.

A bag receiving member 16 is here shown in the form of a pair of curved hooks pivotally connected at one end with the inner end of bar 3 and which are designed to open

upwardly and straddle the bar 3 when in closed locking position whereby the mail bag will be securely fastened on said bar between said hooks.

5 This bag receiving member is mounted on a shaft 17 which extends through the inner end of bar 3 and has coiled springs 18 and 19 wound on its opposite ends, the inner end of each spring being fixed to one of the hooks 10 of member 16 adjacent their pivotally connected ends and the outer ends of said springs being engaged with the bar 3 in advance of shaft 17 so that said springs exert their tension to force said bag receiver downwardly into locking position.

This bag receiving member 16 has a cross bar 20 spanning the space between the inner ends of the hooks thereof and which is designed to be engaged by a catch 21 when 20 in open position whereby said member 16 is held open. This catch 21 is carried by one end of a bell crank lever 22 fulcrumed between the side members of the bar 3 at the rear of shaft 17 so that when said member 25 16 is open, this catch 21 will engage the cross bar 20 and hold said member in open position against the tension of the springs 18 and 19. The lever 22 depends below bar 3 and a forwardly extending arm 23 is connected with its lower end. This arm 23 is 30 slotted longitudinally at 24 and 25, slot 24 which is formed midway the ends thereof being slidably engaged with a headed stud 26 which projects upwardly from a bracket 27 depending from frame 2. The other slot 35 25 of said arm, which is positioned near its free front end has extended therethrough one arm 28 of bracket 27 and which operates as a guide for the arm 23 and prevents 40 lateral displacement thereof.

This bracket 27 is substantially U-shaped in form and the other arm 29 thereof projects above bar 4, being preferably disposed between the side members 4' and 4'' thereof, 45 and has an eye 30 at its projecting end through which a cable 31 passes, said eye forming a guide for the cable. This cable 31 is secured at one end to the bag receiving member 16 near its pivoted end and at its 50 other end is connected with the dog 11, being designed to release said dog from its engagement on the ratchet 10 when the member 16 is swung forwardly into closing position. This release of dog 11 permits shaft 55 9 to rotate under the action of spring 13 and thereby swing the bag delivery hook 15 inwardly and downwardly to cause the mail bags carried thereby to be released and to drop below into a suitable receptacle as will 60 be presently described.

A cross bar or rod 32 is disposed within the members 4' and 4'' at the rear of shaft 9 and is designed to operate as a stop for limiting the opening movement of the bag 65 delivery member 15.

From the above description it will be obvious that when this device is mounted on the arm 1 outside the car door, and the bag receiving member 16 swung upwardly into the position shown in Fig. 1, and engaged by 70 the catch 21, and the member 15 is swung upwardly with the bags to be delivered carried thereby, that when the arm 8 which is pivotally mounted at the front end of the frame 2 engages an obstruction disposed in its 75 path, said arm will be swung inwardly and will be forced into contact with the forward end of the lever arm 23, said arm 23 being preferably provided with a laterally extending loop-shaped head 23' so as to insure its 80 engagement by the inward movement of arm 8. This forcible inward movement of arm 23 will cause the bell crank lever 22 to rock on its fulcrum to thereby disengage catch 21 from the bag receiving member 16 thereby 85 releasing said member, which under the action of the springs 18 and 19 will swing quickly downward into closed position thereby trapping the mail bag which has passed over the upper edge of arm 3 and 90 thus securely hold said bag in engagement with frame 2. This forward and downward swinging of the member 16 operates to disconnect dog 11 from the ratchet wheel 10 thereby releasing said wheel and the shaft 95 to which it is fixed whereby the mail bag carrying member 15 will swing downwardly and inwardly under the action of spring 13, thereby delivering the bags from said member dropping them into a receptacle disposed 100 at the side of the track and which will presently be described. After the train has passed the station, the operator within the car on which this device is mounted may disconnect the frame 2 from the arm 1 and 105 remove it into the car to facilitate the removal of the mail bag from the member 16 and after it has been removed, the apparatus may be again set and positioned outside the door ready for collecting and delivering 110 mail at the next station.

This train carried delivering and catching apparatus is designed especially for co-operation with a box 35 which is provided at the station in lieu of the usual crane and 115 which may be constructed of any suitable material preferably of metal and which is disposed at the station adjacent the track and which the train carrying the apparatus above described is to pass. This box 35 is 120 open at both ends and has a slot 36 extending longitudinally throughout the top thereof to provide for the free passage of the rod 6 which supports frame 2 of the train carried mechanism.

Depending from the top of this box on opposite sides of slot 36 therein, are two forwardly opening hook-shaped brackets 37 and 38 which are designed to support the mail bags to be delivered to the train, it be- 130

ing understood that these bags are stretched across said brackets so that when the train passes the apparatus above described will enter at one open end of the box and pass 5 longitudinally therethrough, the depending arm 8 during this passage coming in engagement with a cross bar 39 disposed below brackets 37 and 38 whereby the hook-shaped receiving member 16 will be caused to close 10 over the mail bag supported on said brackets 37 and 38 in the manner above described and the continued movement of the train forward will then cause the train carried apparatus to pass outwardly at the opposite 15 end of the box, it being understood that the delivery crane or hook 15 has been simultaneously actuated in the closing of the member 16 to release the mail bags carried by said crane 15 and deposit them within 20 the box 35 from which they may be removed after the train has passed.

From the foregoing description, taken in connection with the accompanying drawings, the advantages of the construction and 25 of the method of operation will be readily apparent to those skilled in the art to which the invention appertains and while I have described the principle of operation of the invention together with the device which I 30 now consider to be the best embodiment thereof, I desire to have it understood that the device shown is merely illustrative and that such changes may be made as are within the scope of the claimed invention.

35 I claim:

1. A mail bag delivery and receiving apparatus including a supporting frame, an upwardly opening receiving member, means for closing the receiving member, means for 40 holding the receiving member open, means operable by the engagement therewith of an obstruction for releasing the holding means for the receiving member, a delivery member opening downwardly, a spring to facilitate 45 the opening of said delivery member, means for holding said delivery member closed, and a connection between said receiving member and the holding means for the delivery member whereby the closing of the 50 receiving member will operate to release the delivery member.

2. A mail delivery and receiving apparatus including a supporting frame, an upwardly opening receiving member and a 55 downwardly opening delivery member carried thereby, a dog and ratchet mechanism for holding said delivery member closed, means for closing the receiving member, means for holding said receiving member 60 open, means for releasing the receiving member, and a connection between said dog and ratchet mechanism and said receiving member for releasing said delivery member on the closing of said receiving member.

65 3. A mail bag delivery and receiving ap-

paratus including a supporting frame, a bag receiving member and a bag delivery member carried thereby, said members being pivoted one to open upwardly and the other downwardly, spring means for closing said 70 upwardly opening member, means for holding said upwardly opening member open against the tension of its closing means, a spring exerting its tension to open said downwardly opening member, means operable by engagement with an obstruction for releasing the holding means for said upwardly opening member, means for holding the delivery member closed against the action of its spring, and a connection between 75 said receiving member and said holding means operating to release said downwardly opening member on the closing of said upwardly opening member.

4. A mail bag delivery and receiving apparatus including a supporting frame, a hook-shaped receiving member pivotally mounted at one end to open upwardly from said frame, a spring for normally forcing said member into closed position, means for holding said member in open position against the tension of its spring, an oscillating trip member positioned for actuation by an obstructing object to release said holding means, a spring opened delivery member 95 carried by said frame, means for holding said member in closed position against the tension of its spring and a connection between the receiving member and the means for holding the delivery member in closed 100 position whereby the closing of the receiving member will release the delivery member.

5. A mail bag delivery and receiving apparatus including a supporting frame comprising a suspension member, arms extending laterally therefrom in opposite directions and inclined downwardly toward their free ends, an upwardly opening receiving member pivotally mounted on one of said 105 arms with its free end extending toward the free end of said arm, a spring for normally closing said member, a catch for holding said member in open position against the tension of its spring, a trip member for releasing said catch, means for actuating said trip member comprising a pivotally mounted arm depending from the free end of said arm which carries the receiving member, a 110 downwardly opening delivery member carried by the other arm of said frame, means for holding the delivery member in closed position, and a connection between the receiving member and the holding means for the delivery member whereby the closing of 115 the receiving member will operate to release the delivery member.

6. A mail delivery and receiving apparatus including a supporting frame comprising a rod having a support engaging hook at 120

one end and laterally extending downwardly inclined arms at its other end, a downwardly closing bag receiving member mounted on one of said arms, a downwardly opening bag delivery member mounted on the other arm thereof, springs connected with said members for closing one and opening the other, means for holding the receiving member open against the tension of its spring, means for holding the delivery member closed against the action of its spring, releasing means for the delivery member, and means whereby the closing of the downwardly closing member operates to release the upwardly closing member.

7. A mail bag receiving apparatus including a support, an inwardly swinging bar pivotally mounted on said support, a spring pressed downwardly closing receiving member mounted on said support, a catch for holding said member in open position against the tension of its spring, a bracket depend-

ing from said support, and a releasing member slidably mounted on said bracket and positioned in the path of said inwardly swinging bar whereby said catch is released on the inward swinging of said bar. 25

8. A mail bag catcher including a frame for suspension from a mail car provided with a spring closed receiving member, a catch for holding said receiving member open against the tension of its spring, a trip connected to actuate said catch, and a pivotally mounted arm depending from said frame in advance of said catch operating 30 35 trip and in position to engage it when said arm is swung inwardly to release the catch.

In testimony whereof I affix my signature in presence of two witnesses.

HOBART M. MERIDA.
